[57] CLAIM

The ornamental design of the child's canteen sports bottle, as shown and described.

DESCRIPTION

FIG. 1 is a perspective view of the child's canteen sports bottle showing my new design;

FIG. 2 is a front view thereof;

FIG. 3 is a left side view thereof;

FIG. 4 is a top plan view thereof; and,

FIG. 5 is a bottom view thereof.

The rear view is a mirror image of the front view.

The right side view is a mirror image of the left side view.
